[57] CLAIM

The ornamental design for a cover for a cooler container, as shown and described.

DESCRIPTION

FIG. 1 is a perspective view of a cover for a cooler container showing our new design;

FIG. 2 is a top plan view thereof;

FIG. 3 is a front elevational view thereof;

FIG. 4 is a rear elevational view thereof;

FIG. 5 is a bottom plan view thereof;

FIG. 6 is a left side elevational view thereof; and,

FIG. 7 is a right side elevational view thereof.

The cross-hatching of the material is representative of the overall surface of the claimed design.
